UNITED STATES PATENT OFFICE.

LEO RANNEY, OF NEW YORK, N. Y., ASSIGNOR TO STANDARD OIL DEVELOPMENT COMPANY, A CORPORATION OF DELAWARE.

METHOD AND MEANS FOR SEALING FISSURES IN MINE GALLERIES.

Application filed December 31, 1926. Serial No. 158,179.

This invention relates to improvements in mining operations for the recovery of oil, and comprises methods and means for sealing the fissures or cracks which may be encountered in forming mine galleries. In my co-pending U. S. application Serial No. 14,448, filed March 10, 1925, and other applications, the general oil mining method referred to herein is described and claimed. The present improvements are intended primarily for use as an adjunct to that method, but they may be advantageously employed also for other similar purposes.

As described in Serial No. 14,448, a mine shaft is sunk to a point adjacent an oil-bearing sand, galleries are driven from the shaft above or below the sand, but out of contact with it, mine wells are drilled into the sand, and the oil flowing from the mine wells is collected.

The present invention will be fully understood from the following description, read in connection with the accompanying drawing, in which

25. Fig. 1 is a vertical transverse section through a mine gallery intersecting a fissure, and showing in perspective the inner walls of the gallery;

Fig. 2 is a fragmentary perspective view 30 showing the floor of the gallery and the way in which the top of the fissure is enlarged for the application of a sealing material;

Fig. 3 is a view similar to Fig. 1, and showing means for applying the sealing material; and

35. Fig. 4 is a vertical section on the line IV-IV of Fig. 3.

Referring to the drawings, reference numeral 1 denotes a mine gallery in a lower cap rock 2 underlying an oil sand 3. It will be assumed, for the purpose of illustrating the invention, that the gallery has intersected a fissure or crack 4 which extends into the oil sand. In most cases there will not be a rapid flow of fluids from such a fissure into the gallery and it is easy for workmen to seal the fissure in the manner to be described. High gas pressures rarely prevail in oil sands which are to be exploited by my method. If such pressures are encountered, the work may be suspended for a while until the gas has escaped to a sufficient extent. The mine workings are, of course, to be provided with approved ventilating means; and 55 all other necessary safety precautions are to

be taken. Entry of gas, oil, or water into the gallery should be completely prevented before the collection of oil is begun.

The following procedure is preferably adopted for sealing the fissure. First the 60 rock is cut away along the line of the fissure to form an opening 5 having an inverted wedge shape in cross section. A sealing plate 6, having on its undersurface a thick, soft gasket 7 (e. g. soft rubber), is pressed upon the 65 rock of the gallery floor so as to cover the opening into the fissure. The sealing plate is held in position by jacks 8, which exert sufficient pressure to force the gasket tightly against the rock making a fluid-tight seal. 70 The jacks operate under beams 9, held between the jacks and the gallery roof.

When the plate 6 has been secured in position, sealing material is applied under pressure through a pipe 10 so as to fill the opening 5, and usually also the upper portion of the fissure 4 itself. If the fissure is very narrow the sealing material will not enter it to a substantial depth, but in any case the seal is securely anchored by the inwardly 75 projecting edges of the opening 5. Large fissures should be suitably obstructed to prevent too much sealing material from running into them. A plastic Portland cement-water mixture is generally preferred as the sealing 80 means, but other relatively impervious fluid materials, such as hot tar, may be used. The plate 6 is kept in place until the seal has hardened.

In case there is a high enough gas pressure 90 to force the sealing material out of the opening 5, at least one pipe 11 is provided to tap the fissure at a point considerably below the opening. The pipe 11 is preferably set at an angle, as shown in Fig. 4. As many of these 95 pipes as are required to relieve the pressure may be provided. Where the seal is required to stand considerable pressure, the trough or chamber reamed out at the top of the fissure should be of considerable size.

As soon as the sealing material has hardened in the opening, a cap 12 is fitted on the pipe so as to shut off access of gas to the gallery.

It will be understood that a similar method is used in sealing the fissures on the walls and roof of the gallery. When all fissures have been sealed, the mine wells are drilled and the oil collected.

Various modifications in the preferred em- 110

bodiments shown may be made within the scope of the appended claims, in which it is my intention to claim all novelty inherent in the invention as broadly as the prior art permits.

I claim:

1. In a method of sealing a fissure in a mine gallery, the improvement which comprises pressing a sealing member about the opening of the fissure where it enters the gallery to form a fluid-tight seal between the fissure and the gallery, supplying a sealing material to fill the upper portion of the fissure, retaining the sealing member in place until the sealing material has hardened, and then removing the sealing member.
2. In a method of sealing a fissure in a mine gallery, the improvement which comprises enlarging the fissure to form a chamber where the fissure enters the gallery, and adapted to receive a substantial amount of a sealing material, pressing a sealing plate about the chamber to form a fluid-tight seal between the chamber and the gallery, forcing a plastic sealing material into the chamber and allowing the sealing material to harden.
3. In a method of sealing a fissure from

which fluids tend to escape under pressure into a mine gallery, the improvement which comprises providing a by-pass for such fluids under pressure, and then applying a sealing material in the fissure where it opens into the gallery.

4. Method according to claim 3, in which fluids under pressure are led off from a point in the fissure below the sealing material.

5. An apparatus for sealing the fissures in a mine gallery, and comprising a sealing member, means for forcing the member into fluid-tight engagement about the opening of the fissure into the gallery, and means for introducing a sealing material into the fissure beneath the member.

6. Apparatus according to claim 5, in which the sealing member comprises a plate carrying on its undersurface a gasket of compressible material impervious to fluids.

7. Apparatus according to claim 5, in which a by-pass pipe is provided to tap the fissure and lead off fluids under pressure.

In testimony that I claim the foregoing as my invention, I affix my signature.

LEO RANNEY.
